(57) **CLAIM**

The ornamental design for seating, as shown and described.

DESCRIPTION

FIG. 1 is a perspective view of seating according to the present invention;

FIG. 2 is a rear elevation view of the seating of FIG. 1; FIG. 3 is a side elevation of the seating of FIG. 1, taken on the right side of the seating;;

FIG. 4 is a top plan view of the seating of FIG. 1;

FIG. 5 is a front elevation view of the seating of FIG. 1;

FIG. 6 is a bottom plan view of the seating of FIG. 1; and, FIG. 7 is a side elevation of the seating of FIG. 1, taken on the left side of the seating.

Arm rests are shown as broken lines, and are present only for illustrative purposes and form no part of the claimed design of the invention.
